DANIEL HAYS AND WILLIAM FREE, OF SAN FRANCISCO, CALIFORNIA.

Letters Patent No. 74,821, dated February 25, 1868.

IMPROVEMENT IN FIRE-ESCAPE LADDER.

The Schedule referred to in these Letters Patent and making part of the same.

TO ALL WHOM IT MAY CONCERN:

Be it known that we, DANIEL HAYS and WILLIAM FREE, of San Francisco, county of San Francisco, State of California, have invented an Improved Fire-Escape Ladder; and we do hereby declare the following description and accompanying drawings are sufficient to enable any person skilled in the art or science to which it most nearly appertains to make and use our said invention or improvement without further invention or experiment.

The nature of our invention is to provide a ready and convenient means of sending up or elevating ladders to a greater or less height against a burning building, so that the inmates may escape or the fire be subdued.

To do this a common carriage may be employed, with a rest or holder upon the back part, on which a series of ladders are placed when not extended. At the front end of the carriage I place a turn-table, made much in the usual way. Trunnions are attached to each side of the ladder, operating in upright pillow-blocks placed upon the turn-table. Back of the trunnions and pillow-blocks is placed a hand-roll, resting in upright standards, with a cord or chain passing around it, which extends over a pulley in the upper end of the main ladder, both ends of the rope being fastened to a clip which is attached to a second ladder, which slides along the first or main ladder by using the hand-roller. Extending from the turn-table, placed back of this hand-roller, is another roller, having its bearings on curved arms. This roller has a ratchet, in which a pawl works, having its bearings on a standard upon one of the curved arms. A cord or chain, one end of which is attached to the roller, and the other end to the lower round of the main ladder, passes over a base-plate with a grooved, curved arm, by means of which the ladders are raised at the desired angle.

To more fully illustrate and describe our invention, reference is had to the accompanying drawings and letters marked thereon, of which—

Figure 1 is a side sectional elevation.

Figure 2 is a plan.

Figure 3 is a side elevation with ladders extended.

A represents a carriage, having a flat bar, A', bent at both ends at right angles, and attached to the forward and rear trucks, with an upright rest, a, for the ladders. Upon the forward end of the carriage I place a turn-table, B, constructed much in the usual way, and bolted to the axle. Upright pillow-blocks f f are placed at each side of the turn-table, and trunnions C C are attached to each side of the ladder. These trunnions have their bearings in the pillow-blocks, and support the lower end of the ladder C' at any angle, from a horizontal to a perpendicular. Back of the pillow-blocks are placed upright standards D D, in which a horizontal hand-roller, E, works across the turn-table. A cord or chain, F, is connected to this roller, passing through two slots, a a, and passes around a grooved pulley, b, on the top round of the main ladder, the two ends of the cord being attached to a clip, G, which in turn is connected to the extension-ladder H. The ends of the clip extend below the main ladder, and have a roller, b', which works against the rails of the main ladder when the small ladder is extended or withdrawn. A clip, c, is also placed at the upper end of the main ladder, under which the extension slides. By turning the hand-roller around, to which this cord or chain is connected, the ladder is extended and withdrawn. For holding the ladder to the desired inclination when it is against the building, we employ another hand-roller, I, also attached to the upper part of the turn-table, having its bearings in elevated arms d d. At one end of the roller a collar is formed, and at the other a ratchet, K, in which is a pawl, L, having its bearings in the post l. In the centre of the roller I is made a slot, by which one end of the rope or chain H' is connected, extending over a base-plate, N, with a curved and grooved arm, n. The other end of the rope is attached to the lower round of the main ladder, and by turning the roller the ladder is easily raised to the desired angle, where it is kept in place by the pawl, which engages the teeth on the ratchet of the roller, after which the extension may be thrown up by turning the roller E. By this means fire-ladders may be easily raised to a great height, at any inclination, and changed by the turn-table to any point of a circle, without turning the truck or carriage.

Having thus described our invention, what we claim, and desire to secure by Letters Patent, are—

The combination and arrangement of the curved and grooved arm n with hinged ladder c', winding-roller I, rope H', and platform B, substantially in the manner shown and described, for the purposes set forth.
